UNITED STATES PATENT OFFICE.

ANKER PETERSEN, OF WINTHROP, MASSACHUSETTS, ASSIGNOR, BY MESNE ASSIGNMENTS, TO THE AMERICAN WIREMOLD COMPANY, OF HARTFORD, CONNECTICUT, A CORPORATION OF CONNECTICUT.

CONDUITE.

Application filed June 9, 1919. Serial No. 302,644.

To all whom it may concern:

Be it known that I, ANKER PETERSEN, a citizen of the United States of America, and resident of Winthrop, in the county of Suffolk and State of Massachusetts, have invented new and useful Improvements in Conduits, of which the following is a specification.

This invention relates to conduits for wires, pipes and other conductors requiring a protective or insulating covering.

It has heretofore been customary to form paper, textile, or wire tubings for protection of electric wiring or small diameter tubes by winding or wrapping operations, by weaving operations and sometimes by one or both of these operations in connection with a braiding operation carried out with textile yarns characterized by small diameter and by flexibility, but themselves contributing nothing to the stiffness of the tube and serving merely as a binder or cover for a tube already completed by the structure built up of its remaining elements. The operations of the prior art by which such wrapped or woven textile or composite tubular conduits are built up are not only slow but of such a nature that it is difficult to provide for the longitudinal tensile strength of the conduits so formed. For electrical wiring conduits of this type are required by the insurance underwriters to stand a strain of two hundred or more pounds applied longitudinally of the empty conduit. It is difficult and expensive to provide a wrapped, woven or composite conduit having the desired longitudinal tensile strength because the best practice in the prior art has heretofore required that the stiffening and roundness of the conduit be maintained by a stiff, thick element wrapped about the conduit as the weft of a weaving operation, or as the contacting single spirals of a wrapping operation, and in either case in such a position in the tube as not to add materially to the longitudinal tensile strength.

One object of the present invention is to provide for the improved manufacture of such conduits or tubes by operations which shall be rapid and economical, to economize in the cost of the textile element or ingredient of such conduits, and to provide a tubular structure displaying resistance under ex-

tension longitudinally to decrease of its diameter below a critical minimum and increase in the diameter under longitudinal compression to a limited extent; and to include a paper, wooden, composite or metallic thick, stiff element so arranged in the tube as to form when the tube is in its normal state a practically continuous covering resisting crushing and adding its tensile strength to the longitudinal tensile strength of the tube. Other objects of the invention are to provide a conduit of the characteristics above mentioned adapted to be made by braiding operations adapted to be carried out on a high speed braiding machine, so that the machine-production cost of the product is reduced to a minimum.

In the accompanying drawings,—

Figure 1 is an elevation with the outer covering partly removed of a section of a conduit according to my invention;

Figure 2 is a transverse section of the conduit;

Figure 3 is an elevation of the textile element of the conduit;

Figure 4 is an elevation of the stiff and thick element of the conduit;

Figure 5 is a diagram skeleton elevation showing the position in the fabric of a typical textile and a typical stiffening element.

Referring now to Fig. 1 the braided conduit 1 is substantially entirely composed of the thick, stiff elements 2 laid side by side in spiral interleaved relation in sufficient number to have their transverse sections occupy the entire periphery of the tube. As shown parts of the element 2, see Fig. 2, make up the periphery of the tube. The elements 2 preferably are of hard twisted paper cord which may have a round, flat or oval cross section, the latter being shown in Fig. 2. Preferably these elements 2 are held together by strong but thin interbraided binder elements 3, for instance 2—20's cotton yards of good quality wound and laid into the fabric in multiple parallel relation as shown. Four of the elements 3 may be braided as one, for instance, and the braid may be the 1-and-1 braid of the pattern illustrated, although it will be obvious to braiders that other relations of braided warp and braided weft will produce the desired results, and the structure is not to be understood to be limited to

a 1-and-1 braid. Whatever be the particular pattern of braid care is taken not to disturb the contacting relationship of the stiff, thick elements 2. It will be understood without further explanation that the thin, textile binder elements 3, of whatever material they may be composed, will pass between the adjacent runs of the elements 2 without materially separating them, the tension of the braided strands on the braiding machine mandrel preferably employed being sufficient to mash the elements 3 into elements 2 at their crossing and so to leave a continuous tube of the stiff elements 2. As best shown in Fig. 5 a preferred relationship of diameter to the pitch or twist of both sets of strands, when there are six strands 2, is about one pitch of the spiral to each five diameters in length of the tube.

20 As so formed the tube braided of elements 2 and 3 constituting the conduit proper 1 is an exceedingly strong but sufficiently flexible tube relatively so tight at its crevices as to resist entrance into its central cavity of the waterproof impregnating and covering or insulating material generally used with such conduits.

Any desired braided cover for ornament or structural protection may be applied to 30 the outside of the tube 1; as shown 2-and-2 twill braid of linen, silk, ramie or cotton may be applied on the outside, preferably by a simultaneous operation with that for the forming of the tube 1.

35 While such conduits are sometimes formed in place on the wire they are to cover, it is often the practice to insert the wire or tube to be covered into the conduit. By the construction described, the slight play between the spires of the spiral 2 at their limit of longitudinal compression [and of lateral expansion] and at their limit of longitudinal extension, [and of lateral compression] is sufficient to enable the conduit 40 to be compressed in the direction of its length to receive the rounded end of a wire or tube threaded into it, and then to be locked upon the wire or tube threaded into it by stretching the cover with respect to 45 the wire or tube. An important feature also lies in capacity to soak or dip the tube in impregnating material without having this penetrate to its inner surface.

I claim:

55 1. A tubular conduit comprising a plurality of spirally wound thick stiff elements lying side by side and with their adjacent longitudinal edges substantially in contact and under compressive stress when force is applied tending to elongate the conduit, and means intermeshing therewith for holding said elements together.

2. A tubular conduit comprising a plurality of spirally wound thick stiff elements 60 lying side by side and with their adjacent

longitudinal edges substantially in contact, and means intermeshing therewith for holding said elements together, the direction of said elements being more nearly longitudinal than transverse of the conduit.

70 3. A tubular braided conduit comprising a plurality of stiff thick elements with their adjacent edges substantially in contact with each other and under compressive stress when force is applied tending to elongate 75 the conduit, and a series of flexible, thin binder elements interbraided with said stiff, thick elements whereby stiffness and rigidity against crushing of the conduit wall is provided by the stiff, thick elements held in 80 place by the thin resilient elements.

4. A tubular braided conduit comprising a plurality of stiff, thick elements extending longitudinally of the conduit and with their adjacent edges substantially in contact with 85 each other, and a series of flexible, thin binder elements intermeshed with said stiff elements and also extending lengthwise of the conduit, whereby stiffness and rigidity against crushing of the conduit wall is provided by the stiff, thick elements held in 90 place by the thin, resilient elements.

5. A tubular braid consisting of a spirally wound series of hard, stiff components having their adjacent longitudinal edges substantially in contact throughout the length 95 of the braid and subject to compressive stress upon application of force tending to elongate the conduit, said stiff components being held in place by a crossing series of 100 thin, flexible components.

6. A tubular braid consisting of a spirally wound series of hard, stiff components having their adjacent longitudinal edges substantially in contact throughout the length 105 of the braid and held in place by a crossing series of thin, flexible components, the direction of said elements being more nearly longitudinal than transverse of the conduit.

7. A conduit consisting of a tubular braid 110 having side by side a series of spirally wound relatively hard and stiff yarns, said yarns being so constructed and arranged as to constitute a substantially continuous and unbroken tube, and means intermeshing 115 therewith for holding said yarns in edge-wise contact throughout the greater portion of their adjacent meeting edges.

8. A tubular conduit comprising a braided tube having elements which extend spirally 120 in one direction, collectively constituting a substantially unbroken circumferential wall therefor, and other elements extending spirally in the opposite direction, the elements of the two sets being interbraided at their 125 crossings, characterized by the elements of one set greatly exceeding the elements of the other in width and stiffness whereby the stiffer elements form the wall of the tubular conduit and adjacent stiffer elements are 130

separated only so far as to permit the crossing of the thin binder elements serving to hold them in place.

9. A conduit comprising a series of elements which extend spirally in one direction longitudinally of the conduit constituting a substantially unbroken circumferential wall therefor, and a second series of elements which extend spirally in the opposite direction longitudinally of the conduit, the two series of elements being intermeshed at their crossings, characterized in that the elements of one series greatly exceed those of the other in width and stiffness so that the stiffer elements form the wall of the tubular conduit and adjacent stiffer elements are separated only so far as to admit the crossing of the other and relatively thin elements which serve to bind them in place.

10. A braided tubular conduit consisting of a spirally disposed series of hard yarns and an oppositely disposed spiral series of textile yarns of a thin and pliant nature, the yarns of the first series having their adjacent edges in contact except at the points at which the textile yarns pass between them.

11. A braided tubular conduit consisting of a spirally disposed series of hard paper yarns and an oppositely disposed spiral series of textile yarns of a thin and pliant nature, said paper and textile yarns constituting warp and weft elements respectively, adjacent yarns of the first series normally touching each other substantially throughout their lengths except at the points at which the textile yarns pass therebetween.

12. A tubular braid for use as a conduit characterized by a series of parallel spiral components of relatively large diameter, and means for holding said components in operative relationship consisting of relatively thin textile binder elements wound in and out between them, the adjacent components of the first series contacting with each other except at the points where the textile binders pass therebetween.

13. A tubular conduit comprising two series of strands, the strands of the respective series being interbraided with each other, adjacent strands of one series being substantially larger than those of the other and by longitudinal contact with each other

constituting a substantially continuous wall to resist penetration of impregnating material to the interior of the conduit.

14. A conduit comprising two sets of spirally extending interbraided elements, the elements of one set being arranged with their adjacent edges disposed opposite each other so that upon the application of tensile stress longitudinally of said conduit the elements of said one set will engage one another and be placed under compressive strain whereby to prevent substantial diminution in diameter of said conduit.

15. A tubular conduit comprising a plurality of spirally wound stiff, thick elements lying side by side and with their adjacent longitudinal edges substantially in contact and under compressive stress when force is applied tending to elongate the conduit, means intermeshing therewith for holding said elements together, and a casing enclosing said elements and the means intermeshing therewith.

16. A tubular braided conduit comprising a plurality of stiff, thick elements with their adjacent edges substantially in contact with each other and under compressive stress when force is applied tending to elongate the conduit, and a series of flexible, thin binder elements interbraided with said stiff, thick elements whereby stiffness and rigidity against crushing of the conduit wall is provided by the stiff, thick elements held in place by the thin, flexible elements, and a braided textile tube constituting an outer casing for the conduit.

17. A conduit consisting of a tubular structure comprising two sets of interbraided spirally extending elements, the elements of one set being normally disposed in edge to edge contacting relationship so that upon the application of tensile stress longitudinally of the conduit said contacting elements will be placed under compressive strain whereby to prevent substantial decrease in diameter of said conduit, and an outer tubular casing enclosing said tubular structure and constructed and arranged to resist increase in diameter of said tubular structure under internal pressure.

Signed by me at Boston, Massachusetts, this 3rd day of June, 1919.

ANKER PETERSEN.
